UNITED STATES PATENT OFFICE.

HARRY LENO, OF SANTA BARBARA, CALIFORNIA.

CAR-LIFTING DEVICE.

1,409,457.

Specification of Letters Patent. Patented Mar. 14, 1922.

Application filed January 18, 1921. Serial No. 438,179.

To all whom it may concern:

Be it known that I, HARRY LENO, a citizen of the United States, residing at Santa Barbara, in the county of Santa Barbara 5 and State of California, have invented new and useful Improvements in Car-Lifting Devices, of which the following is a specification.

It is the object of this invention to provide a lifting device for motor vehicles and the like, which is an improvement upon the apparatus described and claimed in my co-pending application for car lifting device, Serial No. 399,835, filed July 29, 1920.

15 The present invention contemplates the provision of improved operating means whereby the respective ends of a vehicle may be independently lifted.

The invention also provides means whereby the lifting mechanism when engaging the automobile frame for lifting the same, will also positively engage the spring supported axles of the vehicle so as to lift the latter with the vehicle and without undue 25 strain upon said springs.

It is a still further object of the invention to provide a construction wherein the elements engaging the ground when lifting a vehicle, are provided with rollers adapted to rest upon the ground so that the elevated vehicle may be moved laterally, said rollers being swung out of the way when the device is not in use. The improved construction also provides means 30 for locking said rollers in operative ground engaging position.

The invention will be readily understood from the following description of the accompanying drawings, in which:

40 Figure 1 is a plan view of a motor vehicle frame provided with the improved lifting means.

Fig. 2 is a longitudinal section on the line 2-2 of Fig. 1.

45 Fig. 3 is an end elevation of the vehicle showing the lifting means in operative position.

Fig. 4 is a detail vertical section through one of the lifting devices.

50 Fig. 5 is a detail horizontal section through the same.

Fig. 6 is a vertical section through the actuating mechanism for the lifting means.

55 Fig. 7 is a horizontal section on the line 7-7 of Fig. 6.

The improved lifting mechanism is substantially similar in its main features to that previously described in my above mentioned co-pending application, and is instanced as employed in connection with 60 an automobile having frame side bars 1, and front and rear axles 2 and 3, carried by springs 4 and 5.

The improved lifting mechanism consists of a jack mounted upon the automobile 65 frame beyond front axle 2, and a similar jack mounted upon the frame beyond the rear axle 3. Each of these jacks consists of a box-like casing 6 extending transversely of the automobile frame and, preferably, 70 supported below the side bars 1 by means of the depending brackets 7. Bearing lugs 8 project upwardly from casing 6 adjacent the respective ends thereof, and pinions 9 are journaled within casing 6 by means of 75 axle bearings 10 projecting beyond one of the faces of said pinions and journaled in the bearing lugs 8. Screw threaded elevating rods 11 are threaded through the pinion 9 so as to project above and below pinions 80 9 and the casing 6.

The pinions 9 are rotated by main shafts 12 and 12^a extending lengthwise of the automobile frame and journaled in the respective casings 6. The ends of these shafts 85 within the respective casings are provided with worm wheels 13 meshing with one of the pinions 9 in each of the casings 6. By this arrangement it will be seen that the reverse rotation of said main shafts will 90 reversely rotate the pinions engaged thereby. Countershafts 14 extend lengthwise of casings 6 and are provided with worm wheels 15 meshing with the second of the pinions 9 within said casings. These countershafts 95 are rotated by main shafts 12 and 12^a as by the bevel gears 16-17.

Main shafts 12 and 12^a are arranged to be independently reversely rotated from the driver's seat of the automobile, so that the 100 lifting mechanism at the respective ends of the automobile may be separately actuated for first lifting the forward end of the car, and then lifting the rear end of the same. For this purpose a gear box 18 is, preferably, 105 received about the adjacent ends of main shafts 12 and 12^a beneath the driver's seat, said gear box being suitably supported from the automobile frame.

An axially shiftable clutch sleeve 23 is 110

keyed upon shafts 12 and 12^a within the gear box, and is adapted to engage either a bevel pinion 19 journaled upon shaft 12, or a similar beveled pinion 19^a journaled upon shaft 12^a. The bevel pinions 19 and 19^a are rotated by a bevel pinion 20, so that by movement of said clutch sleeve either shaft 12 or shaft 12^a will be rotated for lifting the respective ends of the automobile.

10 Sleeve 23 is shifted by a yoke 24 connected to a foot pedal 25 projecting through the gear box, and a spring 26 normally holds the clutch sleeve in engagement with pinion 19^a upon shaft 12^a extending to the front of the automobile, so that when pedal 25 is not actuated, the front end of the automobile will be lifted by rotating pinion 20. By subsequently operating the foot pedal and rotating the pinion, the rear end of the vehicle 20 will be similarly elevated. The means for operating pinion 20 may be similar to that described in my co-pending application and includes a stub shaft 21 operated by a suitable removable crank 22 having a reversely 25 operable handle 28.

The threaded rods 11 are held against rotation relative to the reversely rotatable pinions 9 so that said reverse rotation of the pinions will raise and lower said rods 30 through the threaded connection provided between the latter and the pinions. The means employed for holding the rods 11 of a casing 6 against rotation may consist of an arm 40 extending from one rod to the other 35 and fixed to said rods by threaded engagements 41. Nuts 42 are threaded upon the ends of the rods for retaining the latter relative to the arm 40.

Ground engaging members are carried by 40 the arm 40 and are arranged to be automatically swung into either operative or inoperative position. The ground engaging members consist of arms 43 pivoted by the pins 44 to the respective ends of arm 40. Each of these 45 arms terminate beyond the pivot 44 in a curved finger 45, and below pivot 44 each of the arms is provided with a lug 46. The ground engaging arms are so weighted as to normally depend in upright position from 50 arm 40 with the lugs 46 abutting against the arm 40. In this position, when the elevating rods 11 are lowered relative to the casing 6, the arms 43 will engage the ground so that the casing will be elevated. The casings 6 55 being fixed relative to the automobile frame beyond the front and rear axles thereof will as a consequence cause the automobile frame to be lifted from the ground.

When main shafts 12 and 12^a are rotated 60 in the reverse direction for again elevating rods 11 relative to casing 6 and thus returning the automobile to the ground, the arms 43 thus lifted with the elevating rods will have their fingers 45 engaged by casings 6 so 65 that the arms 43 will be swung upwardly into

substantially horizontal position as shown in dotted lines in Fig. 4. The arms 43 will thus be out of the way when the lifting mechanism is not in use.

The arms 43 at each end of the automobile 70 are connected by cross plates 50, and bearing brackets 51 depending from the same with rollers 52 journaled therein. These rollers are adapted to engage the ground when the lifting mechanism is in operative position, 75 so that after the automobile has been lifted, it may be moved laterally when desired upon said rollers. In order to retain the lifting mechanism in operative position, a rod 55 preferably, extends lengthwise of the vehicle 80 and is received through one of the plates 50 with its threaded end extending through the plate 50 at the opposite end of the vehicle, and engaged by a nut 56, so as to lock the parts in position for use. 85

The casings 6 are preferably, provided with means for engaging the axles of the vehicle, so that when the latter is lifted, the weight of the axles will not be carried by the springs. For this purpose brackets 57 extend inwardly from the respective casing 6 to positions beneath axles 2 and 3, and cushioning means shown as coil springs 58 are preferably carried by the brackets in such position as to engage the axles. By this arrangement it will be seen that the axles will be lifted with the automobile frame when the lifting mechanism is brought into use. 95

Various changes may be made without departing from the spirit of the invention 100 as claimed.

What is claimed is:

1. A vehicle in combination with lifting devices at the respective ends of said vehicle, each of said lifting devices having an actuating shaft terminating within a central transmission case, bevel pinion gears rotatably mounted upon the ends of said shafts and continually engaging a master bevel gear supported upon a rotatable shaft and having means for rotating said shaft, and a clutch mechanism for engaging either of said actuating shafts with their respective pinions. 110

2. A vehicle in combination with lifting devices at the respective ends of said vehicle, each of said lifting devices having an actuating shaft terminating within a central transmission case, bevel pinion gears rotatably mounted upon the ends of said shafts and 120 continually engaging a master bevel gear supported upon a rotatable shaft and having means for rotating said shaft, a clutch mechanism for engaging either of said actuating shafts with their respective pinions, and a single means for shifting said clutch. 125

3. A vehicle in combination with lifting devices at the respective ends of said vehicle, each of said lifting devices comprising a casing supported by said vehicle, screw 130

- threaded jack shafts vertically mounted near the ends of said casing, worm wheels having threaded engagement with said jack shafts, a countershaft suitably journaled in 5 said casing, a worm mounted on one end of the countershaft and engaging one of the worm wheels, a bevel gear mounted on the opposite end of the countershaft and engaging a second bevel gear mounted on the 10 main shaft, and a worm mounted on the main shaft and engaging the second of said worm wheels.
4. A vehicle in combination with lifting devices at the respective ends of said vehicle, 15 said lifting devices comprising a casing, vertically actuated shafts and bearing supports fastened to the lower ends thereof, the upper portion of roller supports being pivoted to said bearing supports, a lug formed with and extending at right angles 20 to said roller supports and adapted to engage the lower sides of said bearing supports when in operative position, a finger curved upwardly and inwardly from the upper ends of the roller supports and 25 adapted to engage the lower side of said casing when raised to inoperative position.

In testimony whereof I have signed my name to this specification.

HARRY LENO.
